ORE COOLING APPARATUS

Application filed December 2, 1929. Serial No. 410,970.

This invention relates to improvements in furnace constructions and to means for cooling ore or other material as discharged from furnaces or other treating apparatus.

5 The objects of this invention include the provision of an inexpensive and highly efficient cooling device of the class above indicated. In preferred examples of the invention, a cooling fluid is passed through a plurality of spaced conduits arranged horizontally or vertically, the material to be cooled being scattered over such contacts and allowed to fall therebetween so that any large lumps are broken up and substantially all particles 10 are brought into contact with the cold conduits or pipes.

Various further and more specific objects, features and advantages will clearly appear from the detailed description given below 20 taken in connection with the accompanying drawings which form a part of this specification and illustrate merely by way of example various embodiments of the apparatus.

25 The invention consists in such novel features, arrangements and combinations of parts as may be shown and described in connection with the devices herein disclosed by way of example, as illustrative of preferred 30 embodiments, together with such novel methods as may also be described herein.

Fig. 1 shows the lower section of a rotary rabble furnace with one form of the invention applied thereto;

35 Fig. 2 is a top plan view of the lower hearth showing this form of the invention;

Fig. 3 shows another form of the invention; and

40 Fig. 4 shows an auxiliary construction that may be employed with either form but is shown in connection with the first form.

This invention has been illustrated in connection with a furnace comprising superposed hearths extending inwardly from an outer cylindrical wall 6 and providing roast-

ing spaces between the hearths which spaces are traversed by rabble arms 7 supported on the usual central double walled shaft 8. Air is forced from a fan through a cooling pipe 9, through the central passage of the shaft into 50 the rabble arms from which it issues into the annular passage of the shaft surrounding the central passage.

In the drawings, the lower hearth 10 is shown as provided with a vertical discharging orifice. Secured to this lower hearth in any suitable manner is a frame or hopper 11, Figs. 1 and 4, carrying a series of conduits or pipes 12 connected through a header 13 with the pipe 9 leading from the fan. The 60 header may be detachably mounted and the pipes 12 may be secured in the header and loosely mounted and fitted in the frame for the purpose of cleaning or replacement.

These pipes may be arranged in tiers and the pipes of adjacent tiers are preferably staggered as shown in Figs. 1 and 4. In these figures the pipes 12 are arranged tangentially and circumferentially of the hearth 65 in the line of travel of the ore as it falls through the discharge orifice and the ore is broken up or separated during its discharge to provide for cooling of substantially every particle of ore.

In the arrangement shown in Fig. 3 the 75 staggered pipes 15 are arranged substantially radially of the hearth or transversely of the path of travel of the discharging ore.

It may be desirable to lower the temperature still more, in which event an auxiliary 80 frame or hopper 16, Fig. 4, containing cooling pipes 17 may be detachably secured to the upper frame 11 as shown.

The air may be forced through these pipes from the fan through the header to which the 85 pipes 12 are connected, or a separate header may be provided for the pipes 17. The upper frame or hopper 11 is preferably flared downwardly as shown and the lower frame or hopper 16 is preferably flared toward its 90

ends as shown to provide for a scattered discharge as the material leaves the frames or hoppers.

If desired, the pipes in either or both of the frames may be connected in continuous fashion with the air entering the system preferably through the lower pipes.

The air discharged from these pipes may be blown into the atmosphere or conducted by suitable means into one or more of the hearth spaces where special temperature conditioning may be desirable.

As shown in Fig. 4 the speed of discharge may be controlled by a cut-off plate 18 which tends to check the flow of the material through the device to any desired extent.

With the above described constructions, it will be observed that as the rabble arms revolve, the rabble teeth will gradually discharge the treated ore over the angularly directed edge of the discharge opening (see Figs. 2 and 3), so that the ore will be scattered throughout the cross-sectional area of the discharge opening and any large lumps will strike against the cooling pipes and become more finely divided. With the staggered arrangement of the cooling pipes in a plurality of tiers it will be apparent that substantially all of the particles of the mass will come into contact with one or more of the cooling pipes to insure uniform cooling.

It is apparent that this invention may be used not only to cool material discharged from a furnace as shown, but also to cool any material caused to move through it by any suitable means.

While we have described our improvements in great detail and with respect to certain preferred forms thereof, we do not desire to be limited to such forms or details, since many changes and modifications may be made and the improvements embodied in widely different forms without departing from the spirit and scope of the invention in its broader aspects. Hence, we desire to cover all modifications and forms coming within the language of any one or more of the appended claims.

What we claim as new and desire to secure by Letters Patent is:

1. The combination with an ore roasting furnace comprising a hearth provided with an ore discharge orifice; of a cooling device secured below said orifice comprising a frame provided with outwardly flaring sides, cooling pipes supported in said sides, a second cooling device comprising a frame secured to said first mentioned frame and provided with sides converging inwardly from the ends of the frame, and a series of cooling pipes supported in said sides.

2. The combination with means for causing material to drop by gravity; of cooling means arranged in the path of the moving material to cause a scattered discharge of the

material and consequent contact between substantially every particle of the material and the cooling means, and means for confining the material as it moves past the cooling means, said confining means being constructed to permit the scattering effect produced by the cooling means.

In testimony whereof we have signed our names to this specification.

HENRY J. HARTLEY.
FREDERICK B. SCHILLING.
